[57] CLAIM

The ornamental design for a fluorescent lighting fixture, as shown and described.

DESCRIPTION

FIG. 1 is a bottom, right side perspective view of a fluorescent lighting fixture showing my new design, the fixture being broken away for convenience of illustration;

FIG. 2 is a bottom plan view thereof;

FIG. 3 is a left side elevational view thereof, the right side being a mirror image;

FIG. 4 is a top plan view thereof; and

FIG. 5 is end elevational view thereof, the opposite side being a mirror image.

FIG. 2

FIG. 3

FIG. 4
